PURIFICATION OF ACETALDOL BY
DISTILLATION

Karl Heinrich Walter Tuerck, Banstead, and
Hans Joachim Lichtenstein, London, England,
assignors to The Distillers Company Limited,
Edinburgh, Scotland, a British company

Application March 6, 1944, Serial No. 525,232
In Great Britain February 24, 1943

10 Claims. (Cl. 202—48)

In order to obtain pure acetaldol, crude acetaldol, as obtained by the condensation of acetaldehyde with alkali and which contains free acetaldehyde and higher polymerised products, is generally distilled. During this distillation, even if it is carried out under high vacuum, a considerable part of the acetaldol resinifies, and high molecular weight unsaturated aldehydes, as well as crotonaldehyde, are formed and this is particularly noticeable when distilling technical acetaldol which contains a considerable proportion of acetaldehyde. These substances exercise an adverse effect on the reactions for which acetaldol is used as starting material. Acetaldol of high purity can be obtained, however, in accordance with the process of the present invention which comprises distilling crude acetaldol in vacuo by leading it into a distillation column in countercurrent to the vapours of a normally liquid hydrocarbon, which is immiscible with acetaldol and has a boiling point of from 170°—300° C. at normal pressure, condensing the distillate and separating the purified acetaldol layer from the hydrocarbon layer. The distillate separates into two layers, the lower one being water-clear monomeric acetaldol which will polymerise to paraldol unless it is kept cool. The hydrocarbon, which forms the upper layer, may be returned to the still from which the vapours rise into the column. The vacuum in the column during the distillation should be maintained at a level which enables a temperature to be maintained at the top of the column not above 90° C. preferably between 70—80° C.

In carrying out the invention, we prefer to introduce the crude acetaldol gradually at a point near the top of the column, whereas the hydrocarbon is evaporated in a separate still and its vapours introduced near the bottom of the column; the residues from the distillation are run off at the bottom of the column. If the residues do not run off separately, but back into the hydrocarbon still, care should be taken that the high-boiling materials form only a small part, preferably not more than $\frac{1}{5}$, of the volume of the hydrocarbon in the still. The present process may be applied with great advantage to acetaldol, containing acetaldehyde, which has been stored for some time and in which a high proportion of higher polymers are present. These higher polymers are depolymerised during the distillation in the column without the formation of resinous matter, whereas, if distilled from a kettle, the major part cannot be evaporated at all without resinification or decomposition to unsaturated

5 volatile aldehydes taking place and the distillate appears more or less coloured.

Crude acetaldol which normally contains about 50% by weight of acetaldehyde may be subjected as such, to the distillation process of the present invention, or it may first be freed from the major part of the acetaldehyde by known methods. Free acetaldehyde passing from the distillation column may be condensed behind the vacuum pump at normal or increased pressure.

10 The following example illustrates the manner in which the invention may be carried into effect.

15 Through a packed column, dodecane was distilled at a pressure of 25 mm. of mercury, while at the top of the column acetaldol, containing about 20% by weight of acetaldehyde, was introduced. The temperature at the top of the still was kept at 75° C. In the condenser a mixture of 3 parts by weight of dodecane and 1 part by weight of acetaldol condensed, whereas in the bottom of the column a small amount of a viscous residue remained. From 450 grams of crude acetaldol, 350 20 grams of pure, water-clear acetaldol were collected as distillate. The two layers in the distillate were separated and the hydrocarbon layer was returned to the still at the bottom of the column.

25 When acetaldol from the same sample was distilled at the same pressure directly from an externally heated vessel, even in the presence of an excess of dodecane, 2,000 grams of acetaldol yielded only 770 grams of a yellowish distillate.

30 In the drawing there is shown diagrammatically the apparatus in which the process of the invention can be carried out.

35 As will be seen this apparatus comprises a packed column, to which reference is made in the foregoing example, and this column is provided with an input near to the base of the column for the vapours generated in the still by the action of the heater.

40 The hydrocarbon vapours of course flow up the column in countercurrent flow to the crude acetaldol which is fed in near the top of the column from the feed tank shown.

45 Leading from the top of the column is a pipe which connects with the condenser and in this condenser the mixture of the hydrocarbon and acetaldol are condensed. The purified acetaldol is withdrawn from the condenser through the draw-off cock shown whilst the upper layer of hydrocarbon is withdrawn through the pipe indicated and conveyed to the still.

50 The whole system is maintained under reduced

pressure by means of the vacuum pump which is shown connected to the condenser.

The column is shown effected with a draw-off cock at the base and through this the high boiling residues passing downwardly through the column can be withdrawn and if desired these can be returned to the still provided that the amount of high boiling materials being fed into the still does not exceed 10% by weight of the hydrocarbon in the still; alternatively, the high boiling residues can be withdrawn from the base of the column and separately dealt with. The apparatus is of course adapted for continuous operation.

A special advantage of our process is that it allows of the use of a vacuum of 10-30 mm. (which is conveniently attainable commercially) and eliminates the detrimental effect which fluctuations in pressure have in the usual straight vacuum distillations of acetaldol.

What we claim is:

1. A process for the purification of crude acetaldol which comprises distilling crude acetaldol in vacuo by leading it into a distillation or fractionating column in countercurrent to the vapours of a normally liquid hydrocarbon, which is immiscible with acetaldol and has a boiling point of from 170°-300° C. at normal pressure, condensing the distillate and separating the purified acetaldol layer from the hydrocarbon layer.

2. A process according to claim 1 wherein the pressure in the said column is so selected that the temperature at the top of the column is not above 90° C.

3. A process according to claim 1 wherein the pressure in the said column is so selected that the temperature at the top of the column is 70° to 80° C.

4. A process according to claim 1 wherein the hydrocarbon layer which is separated off is re-

turned to a still in which the said vapours are generated.

5. A process according to claim 1 wherein the residues from the distillation column are run off separately.

6. A process according to claim 1 wherein the residues from the distillation column are returned to a still in which the hydrocarbon vapours are generated, the amount of high-boiling materials being controlled to a value not in excess of 10% of the volume of the hydrocarbon therein.

7. A process according to claim 1 wherein the said hydrocarbon vapours are introduced into said column near to the base thereof and the crude acetaldol is introduced into said column near to the top thereof.

8. A process according to claim 1 wherein the operating pressure of said column is maintained between 10 and 30 mm. of mercury.

20 9. A process according to claim 1 wherein the crude acetaldol is freed from the major part of the co-present acetaldehyde prior to being introduced into said column.

10. A continuous process for the purification of 25 crude acetaldol which comprises generating the vapours of a normally liquid hydrocarbon, which is immiscible with acetaldol and has a boiling point between 170° and 300° C. under normal pressure, in a still, passing said vapours into a 30 packed column maintained at reduced pressure, introducing crude acetaldol into said column, transferring a mixture of the vapours of said hydrocarbon and acetaldol from the top of the column to a condenser, separating the condensate into two fractions consisting respectively of 35 purified acetaldol and said hydrocarbon, recovering the purified acetaldol and recycling said hydrocarbon fraction to the still.
